UNITED STATES PATENT OFFICE.

HARRISON B. WALTER, OF DANVILLE, ILLINOIS, ASSIGNOR, BY MESNE ASSIGNMENTS, TO
ALREADY BOX COMPANY, OF DANVILLE, ILLINOIS.

BOX.

No. 915,394.

Specification of Letters Patent. Patented March 16, 1909.

Application filed April 24, 1908. Serial No. 428,961.

To all whom it may concern:

Be it known that I, HARRISON B. WALTER, a citizen of the United States, residing at Danville, in the county of Vermillion and 5 State of Illinois, have invented certain new and useful Improvements in Boxes, of which the following is a specification.

My invention relates to an improvement in boxes, and the object is to provide a box 10 which can be made of any heavy paper board, which is creased at certain predetermined intervals for forming the sides of the box, and the ends of the box are formed from flaps which are connected to the sides 15 of the box. The ends of these flaps are preferably held by suitable securing means which are so connected to the end flaps that they can be detached after the box is collapsed.

Another object is to have the ends of the 20 box so connected at the sides that a recess is formed whereby the box can be easily handled.

The invention still further consists in certain novel features of construction and 25 combinations of parts which will be herein-after described and pointed out in the claim.

In the accompanying drawings:—Figure 1 is a perspective view of the box; Fig. 2 is a plan view of the box before it is folded; 30 Fig. 3 is a longitudinal sectional view; Fig. 4 is an end view; and Fig. 5 is a modification.

A, represents the paper or straw board mat which is creased at intervals as at 1, 1, 35 which is folded together and connected as at 2. The end flaps 3, 3 are adapted to be connected to the inner sides of the box as at 4 by some adhesive material. The flaps 3 are creased as at 5, whereby the ends of 40 the flaps are capable of extending across the ends of the box a short distance beyond the center. The flaps are all provided with openings 6, 6, excepting one flap at each end of the box which is provided with a 45 pin 7. When the box is folded for use, the flap having the pin 7 is brought into position, and the openings 6, 6 in the other flaps are placed over the pin. After all the flaps have 50 been placed over the pin, a collar 8 is secured to the pin in any suitable manner, thereby

making a solid box. In having the ends raised by the flaps 3 being bent down against the sides of the box and then outwardly to form the ends, it gives additional strength to the box, as the paper is doubled and protects the contents of the box from damage when the ends are crushed in transit or in any other manner. The raised ends also afford a means for easily handling the boxes as they can be grasped by the 60 ends and a firm grip obtained.

These boxes are adapted to be used for packing cartons, candy, crackers, and like, and the ends on the body portion of the box may be made of any suitable material. 65 These boxes may be shipped to different points in a very small compass, as the body portion can be folded along the creases and the end flaps be folded inwardly so that the entire box will take very little space, and when it is desired to use a box it can be 70 very readily assembled.

In the form shown in Fig. 5, the ends of the flaps are connected to the sides of the box by staples or rivets 9.

It is evident that more or less slight changes might be resorted to in the form and arrangement of the several parts described without departing from the spirit and scope of my invention, and hence I do 80 not wish to be limited to the exact construction herein set forth, but:

Having fully described my invention, what I claim as new and desire to secure by Letters Patent is:

A box comprising sides, independent end flaps being bent, and said bent portions connected to the sides of the box forming recesses, said end flaps having openings formed therein, a pin connected to one of the 90 end flaps adapted to pass through the openings in the end flaps, and a collar received on the pin for locking the flaps together.

In testimony whereof I affix my signature in presence of two witnesses.

HARRISON B. WALTER.
